UNITED STATES PATENT OFFICE

135,069

DESIGN FOR A TOY FIGURE

Lois Bishop Somersett, Oakland, Calif.

Application June 24, 1942, Serial No. 107,336

Term of patent 14 years

To all whom it may concern:

Be it known that I, Lois Bishop Somersett, a citizen of the United States and a resident of Oakland, county of Alameda, State of California, have invented a new, original, and ornamental Design for a Toy Figure, of which the following is a specification, reference being had to the accompanying drawing, forming part thereof.

I claim:

The ornamental design for a toy figure, substantially as shown.

LOIS BISHOP SOMERSETT.
